UNITED STATES PATENT OFFICE

2,606,599

SECTIONAL HASSOCK

James W. Santosuosso, Malden, Mass.

Application February 10, 1950, Serial No. 143,513

4 Claims. (Cl. 155—169)

1

This invention relates to a sectional hassock embodying a plurality of segments movable to an open position providing a plurality of relatively spaced seats and to a closed position providing a single hassock unit. My improved hassock preferably comprises a plurality of sectors pivoted together at the peripheral margin of the hassock. Each segment also preferably comprises a box-like chambered body open at the top for storage purposes and a seat cover pivoted thereto. Other means are also preferably provided for limiting the opening pivotal movement of the segments and for securing the end segments together when they are brought to the closed position. The production of a new and improved sectional hassock of this nature which can be opened up to provide a plurality of seats particularly adapted for use of television spectators comprises the primary object of the invention.

These and other features of the invention will be best understood and appreciated from the following description of a preferred embodiment thereof selected for purposes of illustration and shown in the accompanying drawings in which—

Fig. 1 is a top plan view of a preferred form of the invention,

Fig. 2 is a bottom plan view thereof,

Fig. 3 is a top plan view of the hassock in open position,

Fig. 4 is a front elevation thereof, and

Fig. 5 is an enlarged vertical sectional view through one of the segments.

In the drawings 10 indicates the closed hassock unit embodying a plurality of segments 12. While I have illustrated the hassock as being of cylindrical form and comprising four sectors 12 pivoted together at the peripheral margin of the hassock as by hinges 14, it will be understood that other forms and arrangements can be employed as desired.

Each segment preferably comprises a box-like chambered body 15 open at the top for storage purposes and a seat cover 16 pivoted thereto at 18. A spring latch at 20 is adapted to hold the cover in closed position and the cover is preferably upholstered to form a cushioned seat. The segments are adapted to be open to the position illustrated in Fig. 3 to provide a plurality of seats in alignment.

Each segment is preferably provided with a plurality of studs 21 in the bottom for supporting the segments spaced from the floor and foldable ties, illustrated as pivotally connected links 22 pivotally attached to the segments at the

bottom, serve to limit the opening movement of the segments. The studs provide a space or pocket beneath the hassock for receiving the links when the segments are brought to the closed position of Figs. 1 and 2. A latch hook 24 and a cooperating stud 26 are also provided on the end segments for holding the end segments together with their end faces in contact.

It will now be apparent that I have produced 10 a new and useful hassock for living room purposes that can be conveniently opened up to provide a plurality of seats particularly adapted to serve guests at the television, and, when the seats are not required, the several segments can 15 be placed together with their V-shaped cooperating sides in face-to-face contact to form a hassock embodying the segments thus combined.

Having thus disclosed my invention what I 20 claim as new and desire to secure by Letters Patent is:

1. A hassock comprising a plurality of segments, each substantially triangular in horizontal cross section and having side walls extending from top to bottom of the hassock and including two relatively V-shaped inner side walls and an outer side wall, the segments being relatively movable to an open position providing a plurality of relatively spaced seats and to a closed position providing a single hassock unit with all of the inner side walls in face to face contact and the outer side walls disposed in circular alignment at the periphery of the unit.

2. The hassock defined in claim 1 in which the segments are pivoted together on vertical axes 35 at the junctions of the inner and outer side walls and are relatively movable on the pivots to said open and closed positions.

3. The hassock defined in claim 2 plus foldable ties each attached at its two ends to two pivotally connected segments for limiting the opening pivotal movement thereof, and means providing pockets for receiving the ties when the segments are moved to the closed position.

4. A hassock comprising a plurality of like segments having outer side walls, inner side walls adapted to cooperate with each other and bottom walls, said walls providing a box-like chambered body open at the top for storage purposes, and a seat cover pivoted to the top of each segment and movable to open and closed positions, the segments being relatively movable to an open position providing a plurality of relatively spaced seats and to a closed position providing 50 a single hassock unit with all of said inner side

walls in face to face contact and said outer side
walls disposed in circular alignment at the pe-
riphery of the unit.
